APPARATUS FOR CUTTING A MOVING BROAD STRIP LONGITUDINALLY AND OBLIQUELY

Peter Weisshuhn, Zurich, Switzerland, assignor to Societe a responsabilite limitee Les Ateliers de Constructions Mecaniques C. & A. Holweg, Strasbourg, France

Application January 22, 1954, Serial No. 405,630

Claims priority, application Germany January 22, 1953

6 Claims. (Cl. 164—61)

The present invention has for its object an arrangement for cutting narrow strips with lateral folds intended when cut into sections to form flat bags.

It has already been proposed to cut out of a broad strip of constant breadth one or more narrow strips with lateral folds. The cutting means generally used for this purpose include a plurality of separate cutting rollers over which the successive cuts defining the narrow strips are made. Such conventional arrangements are expensive and intricate and do not generally ensure a faultless cut.

The drawbacks of said known arrangements are removed in accordance with my invention insofar as a separate cutting roller provided with longitudinal and oblique cutters is associated with a corresponding counter-roller for separating any two adjacent narrow strips, said rollers being submitted to rotations of equal variable speeds.

In order to obtain a faultless cutting both for the longitudinal and the oblique cuts, there is provided a novel and advantageous arrangement which is designed so that the cutting and counter-rollers run during the longitudinal cutting operations at a higher speed than the speed of progression of the broad strip between them while they run advantageously at the same speed as said broad strip during the oblique cuts and at any rate always at a smaller speed than during the longitudinal cutting operations.

It is of advantage to resort for the control of the rollers to a pair of elliptical wheels which allow driving the cutting and counter-rollers at variable speeds which are however always equal for the two types of rollers.

In order to allow per revolution four modifications altogether in the speed of the two cooperating rollers provided with two oblique cutters and with two longitudinal cutters, it is of advantage to provide between the pair of elliptical wheels and the two rollers provided each with two longitudinal cutting means and with two oblique cutting means, a transmission adapted to make the elliptical wheels execute two revolutions for each one revolution of the two rollers, whereby the rollers are submitted during their revolution to four modifications in speed.

Accompanying drawings illustrate by way of example a preferred embodiment of the invention. In said drawings:

Fig. 1 is a diagrammatic view of a complete machine for the execution of flat bags.

Fig. 2 illustrates a section of a broad strip cut into three narrow strips.

Fig. 3 is a perspective view of the cutting arrangement according to the invention.

Fig. 4 is a front view, partly sectional, of the same cutting arrangement.

Fig. 5 is a cross-section through line 5—5 of Fig. 4.

Fig. 6 is a partial front view of a section of Fig. 4 on a larger scale.

Fig. 1 illustrates diagrammatically a machine for the execution of flat bags. The machine includes a frame

2

10 with lateral walls 101 and 102 carrying the different parts of the machine. Fig. 1 shows only one lateral wall 101 resting on a base 11. On the right hand side of the frame 10, as seen in Fig. 1, is provided a paper reel 12 carried by a spindle 13 and from which a broad strip of paper 14 of constant breadth may be unwound in the direction of the arrow U. This broad strip is subdivided by a cutting arrangement A into a plurality of narrow strips 15. In the example illustrated in Figs. 1 and 2, there are provided three narrow strips 151, 152, 153. The control means forming part of said cutting means and the actual cutting means will be described with further detail hereinafter.

The three narrow strips 15 are guided over a guiding roller 16 towards compensating means B including a roller 18 secured to a pivotal arm 17 and a cooperating roller assuming an invariable position. One group of narrow strips, say 151 and 153, are guided in the direction of the arrow V over the roller 18 so as to move over a longer track than the remainder of the strip constituted in the present case by the narrow strip 152, which is guided directly over a shorter track from the roller 16 towards the roller 19. A suitable selection of the track lengths, the relationship between which may be modified by shifting the roller 18, may shift the different narrow strips 15 in a manner such that, upon leaving the roller 19, the transverse sectional lines shown in dotted lines in Fig. 2 at 154, 155 and 156 are brought into transverse register with one another.

30 Beyond the compensating means B, the narrow strips 15 are guided in the direction of the arrow X through means C producing the lateral folds, said folds being produced by an inward folding, as shown in dotted lines in Fig. 2.

35 Beyond the longitudinal folding means C are provided gluing means D including a glue container 20, a glue-feeding roller 21 and glue-applying discs 22 adapted to apply the glue over the longitudinal folds. In front of the glue-applying discs 22 is located a roller 23 forming part of the paper-strip driving means E. The roller 23 is driven by the means described hereinafter and the narrow strips 15 are urged against said roller 23 by means of a further roller 24 provided with driving rings. The narrow strips 15 continue their movement beyond said gluing means towards means F cutting the strips transversely along the lines of separation 154—155—156. Said transversely cutting means F include a cutting roller 25 and a counter-roller 26 and the cut sections are transferred thence into means G producing the transverse folds and including a folding cylinder 27 and a transverse folding blade carried by the rings 28; the finished paper bags 29 are formed into a stack at 30.

40 The control of the complete machine forming flat bags is provided by a motor that is not illustrated and which controls the cylinders 27 and 28 through a suitably designed transmission. Further control means, which are not illustrated, control the transverse cutting means F together with a shaft 31 revolvably mounted at 39 and 40 inside the frame 10. The upper end of the shaft 31 carries also a bevel wheel 32 meshing with a further bevel wheel 33 rigid with the above-mentioned driving roller 23. The lower end of the shaft 31 also carries a bevel wheel 34 meshing with a bevel wheel 36 rigid with a shaft 35. The latter is revolvably mounted at 37 and 38 inside the frame 10 and controls the above-mentioned cutting means A through transmission means described hereinafter in detail.

45 The above-described arrangement cooperating with the transmission means referred to but not described controls the movements at the desired relative speeds of the cutting means A, the driving means E, the transverse cutting means F and the transverse folding means G. Thus,

as disclosed hereinafter with further detail, the speed of the strips 14-15 and of the cutting means A is defined in a predetermined manner.

The different parts of the machine illustrated in Fig. 1 except the cutting means A are known per se. They form no part of the invention and are consequently illustrated and described in a cursory manner so as to allow the arrangement according to the invention to be more readily understood. Hereinafter, only the cutting means A will be disclosed with further detail, reference being made to accompanying Figures 3 to 6.

The above-mentioned shaft 35 carries a bevel wheel 50 meshing with a further bevel wheel 51, which latter is rigid with a shaft 52 revolvably mounted at 53 in the side wall 101 of the frame through the agency of a chain 54 (Fig. 5). The shaft 52 carries further an elliptical wheel 55 meshing with a further elliptical wheel 56. The latter elliptical wheel 56 is rigid with a shaft 57 revolvably carried at 58 by the side wall 101, said shaft 57 carrying at its end a toothed wheel 59 the distance of which with reference to the elliptical wheel 56 is defined by spacing rings 60 (Fig. 4). The toothed wheel 59 meshes with a toothed wheel 61 rigid with a shaft 62 carried at 63 and 63 in the side walls 101 and 102. The above-mentioned toothed wheel 61 meshes in its turn with a toothed wheel 65 rigid with a further shaft 68 revolvably carried at 66 and at 67 between the side walls 101 and 102. As shown in Fig. 4, the side walls 101 and 102 of the frame are connected by a tie-rod 69 secured by means of nuts 70 to said side walls.

The shaft 68 carries the actual cutting rollers while the shaft 64 carries the counter-rollers which are slidably mounted on it. For this purpose, the shaft 68 is provided with a groove 681 engaged by a wedge not illustrated which serves for guiding the cutting rollers. After positioning of the cutting rollers to suit the desired breadth of bag, said cutting rollers are secured in position by means of clamping screws 71. The number of cutting and counter-rollers is equal to four in the example illustrated corresponding to the obtention of three narrow strips.

Fig. 6 illustrates a cutting roller shown separate with the corresponding counter-roller on a larger scale. The shaft 68 carries a plate 72 of which the side directed towards the right hand side of Fig. 6 corresponds in shape to the desired shape of the narrow strips. To said side of the plate is applied under pressure a cutter 79 through the agency of the parts 73, 74 and 75 which are held fast by screws 76, 77 and 78. The actual cutter includes in succession a longitudinally cutting section 791, an oblique cutting section 792 and a further longitudinally cutting section 793. The other side of the cutter includes a further oblique cutting section which cannot be seen in Fig. 6. After the counter-roller has been suitably positioned both axially and radially, said counter-roller is also secured through clamping screws 80. Each counter-roller 81 is secured to the shaft 64 through a screw or pin 80, said counter-roller being provided with longitudinal grooves 811 and 813 extending in adjacent transverse cross-sections and connected by oblique grooves 812, so as to correspond to the different sections 791, 793 and 792 of the cutter 79.

The transmission ratios between the different toothed wheels are selected so that the wheels 50 and 51 increase the speed in a ratio as between 1 and 2, while the toothed wheels 59 and 61 reduce the speed by an equal amount. The toothed wheels 61 and 65 have equal numbers of teeth and the same is the case for the elliptical wheels 55 and 56.

The above-disclosed transmission ratios are such that the modifications in speed are provided twice for each revolution of the toothed wheels 61 and 65 under control of the elliptical wheels 55 and 56, in a manner such that the high speed appears for the two longitudinal cuts and the lower speed for the two oblique cuts.

Now, if it is desired to modify for a constant breadth of bag the lengths of the successive bag sections unwound from the reel, it is possible for instance to modify the speed of the strips 14 or 15, for instance by changing the bevel wheels 32 and 33 or by modifying the transmission at another point, so that the ratio between the speed of the cutting means and the speed of the paper strip is modified. When the speed of the cutting rollers and of the cooperating counter-rollers remains unaltered, the increased speed of the strip leads obviously to an increase in the length of the bag sections that are being unwound.

The arrangement of the transmission illustrated in Figs. 3 to 5 is designed in accordance with the invention so that the speed of the cutting rollers and of their counter-rollers is higher than the speed of the paper strip so as to obtain a clean cut. In the execution of the oblique cuts, it is however necessary, in order to prevent any tearing or deformation of the paper strip for the speed of the oblique cutter to be equal to or at least not very different from the speed of the paper strip, the difference between last-mentioned speeds being held below a predetermined value.

What I claim is:

1. A machine for cutting bag blanks out of a broad strip, comprising a shaft, a number of cutting rollers carried by said shaft and including each a peripheral cutter constituted by two longitudinal sections in two slightly spaced cross-sections and two oblique sections interconnecting the two longitudinal sections to form therewith a continuous cutter outline adapted to cut a zig-zag line, a second shaft, parallel to the first shaft, counter-rollers cooperating with the corresponding cutting rollers, carried by the second shaft and leaving a gap between them and the cutting rollers, means for feeding the broad strip through the gap between the cutting rollers and the counter-rollers to cut said strip into a number of narrow longitudinal strips defined by the number of cutting rollers and counter-rollers, means for driving the two shafts at constantly equal speeds and transmission means controlling said driving means and adapted to modify said speeds periodically during each revolution of the shafts by increasing the speed of the cutting rollers over that of the broad strip during engagement of the latter by the longitudinal sections of the cutters and by substantially equalizing the speed of the cutting rollers with that of the broad strip when the latter is engaged by the oblique cross sections of the cutters.

2. A machine for cutting bag blanks out of a broad strip, comprising a shaft, a number of cutting rollers carried by said shaft, said cutting rollers being shiftable longitudinally of said shaft and including each a peripheral cutter constituted by two longitudinal sections in two slightly spaced cross-sections and two oblique sections interconnecting the two longitudinal sections to form therewith a continuous cutter outline adapted to cut a zig-zag line, a second shaft, parallel to the first shaft, counter-rollers cooperating with the corresponding cutting rollers, carried by the second shaft and leaving a gap between them and the cutting rollers, said counter-rollers being shiftable longitudinally of the second shaft for registering with said cutting rollers, means for feeding the broad strip through the gap between the cutting rollers and the counter-rollers to cut said strip into a number of narrow longitudinal strips defined by the number of cutting rollers and counter-rollers, means for driving the two shafts at constantly equal speeds and transmission means controlling said driving means and adapted to modify said speeds periodically during each revolution of the shafts, the speed of the cutting rollers being higher than the speed at which the broad strip is fed thereto during engagement of the broad strip by the longitudinal sections of the cutters and the speed of said cutting rollers being substantially the same as the feeding speed of the broad strip during engagement of the broad strip by the oblique sections of the cutters.

3: A machine for cutting bag blanks out of a broad

strip, comprising a shaft, a number of cutting rollers carried by said shaft and including each a peripheral cutter constituted by two longitudinal sections in two slightly spaced cross sections and two oblique sections interconnecting the two longitudinal sections to form therewith a continuous cutter outline adapted to cut a zig-zag line, a second shaft, parallel to the first shaft, counter-rollers cooperating with the corresponding cutting rollers, carried by the second shaft and leaving a gap between them and the cutting rollers, means for feeding the broad strip through the gap between the cutting rollers and the counter-rollers to cut said strip into a number of narrow longitudinal strips defined by the number of cutting rollers and counter-rollers, means for driving the two shafts at constantly equal speeds and transmission means controlling said driving means and adapted to modify said speeds periodically during each revolution of the shafts, the speed of the cutting rollers being higher than the speed at which the broad strip is fed thereto during engagement of the broad strip by the longitudinal sections of the cutters and the speed of said cutting rollers being substantially equal to the feeding speed of the broad strip during the engagement of the broad strip by the oblique sections of the cutters.

4. A machine for cutting bag blanks out of a broad strip, comprising a shaft, a number of cutting rollers carried by said shaft and including each a peripheral cutter constituted by two longitudinal sections in two slightly spaced cross-sections and two oblique sections interconnecting the two longitudinal sections to form therewith a continuous cutter outline adapted to cut a zig-zag line, a second shaft, parallel to the first shaft, counter-rollers cooperating with the corresponding cutting rollers, carried by the second shaft and leaving a gap between them and the cutting rollers, means for feeding the broad strip through the gap between the cutting rollers and the counter-rollers to cut said strip into a number of narrow longitudinal strips defined by the number of cutting rollers and counter-rollers, means for driving the two shafts at constantly equal speeds and transmission means controlling said driving means and including a pair of inter-engaging elliptical wheels controlling said driving means and adapted to modify said speeds periodically during each revolution of the shafts, said transmission means increasing the speed of the cutting rollers over that of the broad strip during engagement of the latter by the longitudinal sections of the cutters and substantially equalizing the speed of the cutting rollers with that of the broad strip during engagement of the latter by the oblique sections of the cutters.

5. A machine for cutting bag blanks out of a broad strip, comprising a shaft, a number of cutting rollers carried by said shaft and including each a peripheral cutter constituted by two longitudinal sections in two slightly spaced cross-sections and two oblique sections interconnecting the two longitudinal sections to form therewith a continuous cutter outline adapted to cut a zig-zag line, a second shaft, parallel to the first shaft, counter-rollers cooperating with the corresponding cutter rollers, carried

by the second shaft and leaving a gap between them and the cutting rollers, means for feeding the broad strip through the gap between the cutting rollers and the counter-rollers to cut said strip into a number of narrow longitudinal strips defined by a number of cutting rollers and counter-rollers, means for driving the two shafts at constantly equal speeds and transmission means controlling said driving means and including a pair of inter-engaging elliptical wheels, means driving said elliptical wheels and a gear connecting the elliptical wheels with the shaft driving means, whereby said elliptical wheels execute two revolutions for each revolution of the shafts carrying the cutting rollers and the counter-rollers to make said rollers assume four modifications in speed during each of their revolutions, said transmission means increasing the speed of the cutting rollers over that of the broad strip during each engagement of the latter by the longitudinal sections of the cutters and substantially equalizing the speed of the cutting rollers with that of the broad strip during engagement of the latter with the oblique sections of the cutters.

6. A machine for cutting bag blanks out of a broad strip, comprising a shaft, a number of cutting rollers carried by said shaft and including each a peripheral cutter constituted by two longitudinal sections in two slightly spaced cross-sections and two oblique sections interconnecting the two longitudinal sections to form therewith a continuous cutter outline adapted to cut a zig-zag line, a second shaft, parallel to the first shaft, counter-rollers cooperating with the corresponding cutting rollers, carried by the second shaft and leaving a gap between them and the cutting rollers, said counter-rollers being provided each with two annular peripheral grooves connected with two oblique grooves and spaced by a distance equal to the spacing of the longitudinal sections of the cutter in the corresponding cutting roller, said longitudinal sections being adapted to engage the corresponding grooves in the counter-roller and the oblique sections being adapted to engage the oblique grooves in the counter-roller, means for feeding the broad strip through the gap between the cutting rollers and the counter-rollers to cut said strip into a number of narrow longitudinal strips defined by the number of cutting rollers and counter-rollers, means for driving the two shafts at constantly equal speeds and transmission means controlling said driving means and adapted to modify said speeds periodically during each revolution of the shafts, said transmission means increasing the speed of the cutting rollers over that of the broad strip during engagement of the latter by the longitudinal sections of the cutters and substantially equalizing the speed of the cutting rollers with that of the broad strip during engagement of the latter by the oblique sections of the cutters.
